UNITED STATES PATENT OFFICE.

JOHN M. BUFFT, OF TUCSON, ARIZONA.

RAIL JOINT.

Application filed July 17, 1925. Serial No. 44,269.

This invention relates to certain new and useful improvements in rail joints, and has more particular reference to an improvement of rail joints of that type wherein provision is made for permitting expansion and contraction of the joined rail sections.

When the adjacent ends of rail sections are so joined and formed that the tread portions thereof are normally spaced apart but 10 may come together when the rail sections expand, constant pounding of the wheels of rolling stock results in distortion or mutilation of the ends of the tread portions of the rail sections so as to produce projections on 15 the latter which resist proper expansion of the rail sections and which are often spread when the rail sections expand to present irregularities on the tread surfaces of the rail sections. These irregularities cause serious 20 pounding and jolting when the wheels of the rolling stock pass thereover, and in some cases cause derailing of the rolling stock.

It is accordingly an object of the present invention to provide a rail joint wherein the 25 adjacent ends of the rail sections to be joined are so formed as to prevent the tread portions of the rail sections from coming together and to accordingly prevent the projections so produced thereon from resisting 30 the expansion of the rail sections and becoming spread to produce the objectionable irregularities.

Another object is to provide a rail joint of the above character which is extremely 35 simple and durable in construction.

Other objects will appear as the nature of the invention is better understood, and the same consists in the novel form, combination and arrangement of parts hereinafter more 40 fully described, shown in the accompanying drawing and claimed.

In the drawings, wherein like reference characters indicate corresponding parts throughout the several views,

45 Figure 1 is a fragmentary side elevational view showing the adjacent ends of a pair of rail sections joined in accordance with the present invention.

Figure 2 is a vertical transverse section 50 taken substantially upon line 2—2 of Figure 1.

Figure 3 is an enlarged fragmentary perspective view of an end portion of one of the rail sections shown in Figure 1, and

Figure 4 is a fragmentary horizontal sec-

tion taken substantially upon line 4—4 of Figure 1.

Referring more in detail to the drawing, 5 and 6 indicate the aligned adjacent rail sections, the adjacent ends of which are to be joined. In accordance with the present invention the adjacent ends of the rail sections 5 and 6 are formed as shown with respect with one of the same in Figure 3 so that the web 7 and base 8 of each rail section 65 project slightly beyond the tread portion 9 thereof and so that the end edges of the portions 7 and 8 provide a flat vertical surface while the end edge of the tread portion 9 also forms a flat vertical surface. It will 70 thus be seen that when the rail sections 5 and 6 are disposed in end to end relation the end edges of the web and base portions 7 and 8 of said rail sections will come together when said rail sections expand but the adjacent edges of the tread portions 9 will be maintained in slightly spaced relation.

Thus when the rail sections expand, the end edges of the webs and bases thereof may come together, but the ends of the tread portions will be maintained thereby in spaced relation, and any ordinary projections produced on the ends of the tread portions, by pounding of the wheels of rolling stock thereon, will not interfere with the 85 expansion of the rail sections, and will not be spread by the treads coming together, so that the objectionable irregularities will not be produced. The fact that the web and base portions of the rail sections only pro-

ject slightly beyond the tread portions results in the production of a space between the tread portions which is so narrow as to not have a serious pounding effect when the wheels of the rolling stock pass thereover. 95 Furthermore, by reason of the space between the adjacent ends of the tread portions of the rail sections, oiling of the rail joints is facilitated.

For joining the rail sections 5 and 6 to 100 permit their relative expansion and contraction, similar fish plates 10 are placed against opposite sides of the web portions 7 of the rail sections 5 and 6 and securely held in place by means of pairs of bolts 11 having 105 nuts 12 threaded thereon. The pair of bolts at one side of the joint extend through circular openings in the web of one rail section and in the adjacent ends of the fish plates 10, while the bolts at the other side of the 110

joint extend through circular openings in the web of the other rail section but through horizontally elongated slots 13 in the other ends of the fish plates 10 so that relative movement between the rail sections 5 and 6 in a direction longitudinally of the latter is permitted. From the foregoing description it is believed that the construction and operation as well as the advantages of the present invention will be readily understood and appreciated by those skilled in the art.

Minor changes may be made without departing from the spirit and scope of the invention as claimed.

16 15 What I claim as new is:

1. In a rail joint, a pair of meeting rail sections having their adjacent ends formed with the web and base portions thereof projecting slightly beyond the tread portions of the same, and means connecting the adjacent ends of said rail sections for permitting relative longitudinal movement of the same.
2. In a rail joint, a pair of meeting rail sections having their adjacent ends formed with the web and base portions thereof projecting slightly beyond the tread portions of the same, and means connecting the adjacent ends of said rail sections for permitting relative longitudinal movement of the same, the end edges of the web and base portions of each rail section providing flat vertical surfaces and the end edge of the tread portion of each rail section providing a flat vertical surface.
3. In a rail joint, a pair of meeting rail sections having their adjacent ends formed with the web and base portions thereof projecting slightly beyond the tread portions

of the same, and means connecting the adjacent ends of said rail sections for permitting relative longitudinal movement of the same, the end edges of said web and base portions of the rail sections being adapted to lie in contiguous relation for preventing the tread portions of the rail sections from coming together.

4. A traction rail comprising a conventional base, web and ball portion, which ball portion is slightly cut away at a rail end so that when positioned adjacent a companion rail ball there is present a permanently open space between the rail balls so that frictional contact thereof is eliminated in vertical movement of a rail due to traction thereover whereby chipping of the rail top surface with a consequent battered end is prevented.

5. In combination, traction rails each comprising a conventional base, web and traction portion, which traction portion is slightly cut away at a rail end to provide clearance leaving the base and web intact to effect the usual rail joint and conventional means for securing said rails together, substantially as and for the purposes set forth.

6. In combination, traction rails each comprising a conventional base, web and ball portion, which ball portion is slightly cut away at a rail end to provide clearance, leaving the base and web intact to effect the usual rail joint, a rail having a cut ball portion being opposed to the cut end of a rail and a conventional fish plate for securing said rails together.

In testimony whereof I affix my signature.

JOHN M. HUFFT.
